UNITED STATES PATENT OFFICE.

ALBERT C. FISCHER, OF CHICAGO, ILLINOIS.

METHOD OF PRODUCING SELF-SPACING SHINGLES.

Application filed September 6, 1921. Serial No. 498,862.

To all whom it may concern:

Be it known that I, ALBERT C. FISCHER, a citizen of the United States, residing at Chicago, in the county of Cook and State 5 of Illinois, have invented certain new and useful Improvements in Methods of Producing Self-Spacing Shingles, of which the following is a specification.

This invention relates to covering members to be applied to a roof or other surface to render the same weatherproof, and has for its object to provide a method of producing shingle-like covering members from sheet material in a form which, when 10 the shingles are assembled upon the surface to be protected and in abutment along the lateral lines of their covered or overlapped portions, will be spaced along the sides of their weathering or exposed portions; also to provide shingles of this kind which may be reversed in position with 15 the same effect.

In carrying out the invention, a sheet of material, such as roofing felt or the like, 20 is punched at intervals along its intermediate portion corresponding substantially to the transverse dimensions of shingles to be formed, and is then severed upon intersecting lines, one of which bisects the 25 openings transversely to their greater dimension, while other severing lines either coincide with side lines of the apertures punched in the sheet or intersect said apertures; the effect being that each shingle 30 produced by the severing process issues in approximately quadrilateral form, but with an offset between the exposed or weathering portion thereof and the portion which is overlapped when in use. Repetition of the 35 punching permits the development of offsets at opposite ends and sides of the shingle, so that they are reversible in position. A modified method of punching consists in locating the apertures alternately on opposite sides of a severing line which affords 40 another method of accomplishing the same result.

In the accompanying drawing—

Figures 1 and 2 represent two sheets 45 punched in the manner stated and having indicated thereon severing lines at right angles to each other, one of which extends transversely of the apertures while the other extends longitudinally thereof, and each coincident with one side of an aperture in

Figure 1, or longitudinally through an intermediate portion thereof in Figure 2.

Figures 3 and 4 represent shingles produced by the method of punching and cutting shown in Figures 1 and 2.

Figures 5 and 6 represent shingles having offsets at opposite ends and sides rendering the shingles reversible in position with the same effect in either position as secured by the form shown in Figures 3 and 4.

Figure 7 is a view showing a modified method of punching the sheet, with the effect of producing reversible shingles.

Referring to Figure 1, A represents the sheet which is punched with apertures a 70 and severed on the line b which extends transversely through all of said apertures, also on the lines c which coincide with the respective apertures; in this instance with one side thereof. The result of this method 75 of punching and cutting is the right hand shingle D (Figure 3), together with its overlapping portion d of full width, weathering portion d' of narrower width, and the offset d^2 between said portions; 80 also the left hand shingle E (Figure 4) with its broader overlapping portion e , its narrower weathering portion e' , and its offset e^2 . Shingles such as those represented by either D or E, when all of the same 85 kind, can be placed side by side with their broad longitudinal margins in abutment and their offsets d^2 all presented in the same direction and the result will be spaced weathering portions d' in the case of shingles D, or a similar arrangement in the 90 case of shingles E.

As shown in Figure 7, apertures a' , a^2 may be formed alternately on opposite sides of the severing line c' and the severing lines 95 b' followed as in the previous instance, with the result that reversible shingles F and G will be provided, either end of which may be used as a weathering portion or an overlapping portion, and with the result 100 that if all the shingles used are of the single type F, single spaces will result from the offsets f^2 , or if of the single type G, single spaces will result from the offsets g^2 ; but if the forms F and G are used alternately, spacings equivalent to the offset f^2 plus the offset g^2 may be developed in line with each alternate longitudinal abutment while each intermediate longitudinal abutment is without spacing.

The foregoing are only some of the uses that may be served by shingles produced in the manner described, but will suffice to illustrate the invention.

5. I claim:

1. The method of producing shingles from sheets, which consists in punching a sheet at intervals corresponding substantially to the width of shingles to be produced, severing said sheet on a line extending transversely of a series of apertures so formed to produce reduced shingle ends, and also severing said sheet on lines producing side edges which meet said apertures.
10. 2. The method of producing shingles from sheets, which consists in punching a sheet at intervals corresponding substantially to the width of shingles to be produced, severing said sheet on a line extending transversely of a series of apertures so formed to produce reduced shingle ends, and also severing said sheet on lines producing side edges which meet said apertures; a severing line extending in the longitudinal direction of an aperture being in a cutting plane which lies between the side lines of said aperture.
15. 3. The method of producing shingles from sheets, which consists in punching a sheet at

intervals corresponding substantially to the width of shingles to be produced, severing 30 said sheet on a line extending transversely of a series of apertures so formed to produce reduced shingle ends, and also severing said sheet on lines producing side edges which 35 meet said apertures; a severing line which extends in the longitudinal direction of an aperture being coincident with one side thereof.

4. The method of producing shingles from sheets, which consists in punching a sheet at 40 intervals corresponding substantially to the width of shingles to be produced, severing said sheet on a line extending transversely of a series of apertures so formed to produce reduced shingle ends, and also severing said 45 sheet on lines producing side edges which meet said apertures; a severing line which extends in the longitudinal direction of an aperture being coincident with one side thereof; and the rows of apertures being 50 multiplied and those in alternate rows lying on opposite sides of the severing lines which coincide with the side lines of said apertures.

In testimony whereof I have hereunto signed my name.

ALBERT C. FISCHER.
